UNITED STATES PATENT OFFICE.

KARL STEINBECKER, OF CHARLOTTENBURG, GERMANY, ASSIGNOR TO GENERAL ELECTRIC COMPANY, A CORPORATION OF NEW YORK.

CYLINDER CONSTRUCTION FOR MULTIPLE-PISTON ENGINES.

1,157,335.

Specification of Letters Patent.

Patented Oct. 19, 1915.

Application filed August 7, 1912. Serial No. 713,749.

To all whom it may concern:

Be it known that I, KARL STEINBECKER, a subject of the King of Prussia, residing at Charlottenburg, Germany, have invented 5 certain new and useful Improvements in Cylinder Construction for Multiple-Piston Engines, of which the following is a specification.

This invention relates to internal combustion engines, and especially to those in which there are two pistons working in opposite directions in the same cylinder.

The object of the invention is to enable 10 a free expansion of the cylinder to take place, so as to avoid strains and warping.

Moreover, the invention simplifies the construction and assembling of the engine and improves its operation.

To accomplish these results, the cylinder 20 is made in one piece and is attached to the engine frame at a point outside of the zone of combustion, so far as this is possible, as hereinafter set forth more at length and as shown in the accompanying drawings, in 25 which—

Figure 1 is a longitudinal section of a cylinder and frame embodying my improvements; and Fig. 2 is a modification of the same.

30 In the examples selected the cylinder 1 is arranged with its axis vertical, but this is immaterial, as the invention is applicable to horizontal engines. The pistons are not shown, but it will be readily understood by 35 those skilled in the art that there are two pistons, one in each end portion of the cylinder, and so connected to the crank shaft as to reciprocate in opposite directions simultaneously. The pistons control the inlet 40 ports 2 for the supply of scavenging air and charging air, and the ports 3 for carrying off the waste gases. The fuel is admitted to the combustion chamber 4, which lies between the ports 2 and 3, through injection 45 devices, not shown, which are inserted at 5.

The lower portion of the cylinder passes 50 through a box-like frame 6 in which is a jacket 7 preferably integral with said frame and concentric with the cylinder, forming a space 8 for a cooling medium. The walls of this jacket are provided with nozzles 9 which register with the air inlet ports 2, and make a fluid-tight joint with the exterior of the cylinder at that point. Mounted upon the 55 frame, but preferably not integral there-

with, is a tubular stool or jacket 10, concentric with the cylinder and (in Fig. 1) having at its upper end a suitable surface to receive a flange 11 on the cylinder by which said cylinder is supported. This flange is 60 located above the horizontal plane of the exhaust ports 3, so that it is outside of the zone of combustion defined by the combustion chamber 4. The jacket 10 has nozzles 12 registering with the exhaust ports 3 and 65 making a fluid-tight joint with the cylinder at that point. It is also provided with openings 13 for the fuel injection devices mentioned above.

In Fig. 2, the upper portion of the cylinder is provided with a cooling jacket 14 preferably cast integral with the cylinder and with the jacket 10, so that in this modification there are but two parts, to wit, the cylinder with its jackets 10, 14 and the frame 70 with its jacket 7. The spaces 15 for the cooling medium in the jackets 10 and 14 are in communication by passages through the bridge pieces 16 between the exhaust ports 3.

The invention offers, over the constructions heretofore known, advantages as regards casting and engineering. The employment of a working cylinder made in one piece, in the sense of the invention, permits the engine body to be composed of a few 85 parts which may be cast without any difficulty, and permit the engine to be set up without jarring. The advantage from an engineering standpoint consists principally 90 in the fact that the cylinder walls, at the places which are most exposed to the heat of combustion, have no dividing joint which can be kept tight only with great difficulty on account of incomplete cooling. The new method of construction permits, furthermore, a free expansion of the cylinder both 95 ways from its supporting flange, and quite independently of its cooling jackets, so that the strains in the engine body, in a cycle of 100 operation, may completely equalize themselves. The connection of the central cooling jacket 10 with the cylinder at one end only obviates the difficulties which result 105 from the employment of cooling jackets which are cast solid with the cylinder at both ends, by reason of the disturbing effects of the strains always contained in such a casting.

It is evident that the cylinder may be supported at some other point than at the place 110

where the flange 11 is shown, but it is not recommended to locate the place of support within the zone of combustion, on account of the interference with the cooling effect.

5 When located elsewhere than as shown in the drawings, the jackets would have to be slightly modified to suit the changed conditions.

In accordance with the provisions of the 10 patent statutes, I have described the principle of operation of my invention, together with the apparatus which I now consider to represent the best embodiment thereof; but I desire to have it understood that the apparatus shown is only illustrative, and that 15 the invention can be carried out by other means.

What I claim as new and desire to secure by Letters Patent of the United States, is:—

20 1. An internal combustion engine having a one piece cylinder adapted for use with two oppositely moving pistons, a frame in which said cylinder has a sliding fit, and means carried by the frame forming a water jacket for the cylinder and also a support for supporting said cylinder at a single point beyond the zone of combustion, whereby said cylinder is free to expand longitudinally through the frame without getting out 30 of alinement.

2. An internal combustion engine having a one piece cylinder for use with two oppositely moving pistons, a frame in which said cylinder has a sliding fit, and a cooling 35 jacket surrounding the zone of combustion of said cylinder, and attached to said cylinder beyond the zone of combustion.

3. An internal combustion engine having a cylinder adapted for use with two oppositely-moving pistons, a frame, and a jacket 40 mounted on the frame, said jacket surrounding the cylinder and supporting it only at one end.

4. An internal combustion engine having

a one piece cylinder adapted for use with 45 two oppositely-moving pistons, a frame, a jacket rising above the frame, and a flange on the cylinder resting on the upper end of the jacket and affording the cylinder its sole support.

5. An internal combustion engine having a cylinder adapted for use with two oppositely-moving pistons, a frame, a jacket rising above the frame and surrounding the combustion chamber of the cylinder, a flange 55 on the cylinder resting on the upper end of the jacket and affording the cylinder its sole support and a jacket in said frame surrounding the lower portion of the cylinder.

6. In an internal combustion engine, the 60 combination of a receiver having openings in its opposite walls and a cylinder with an inner wall mounted in said openings and surrounded by a jacket which is mounted on one of the walls of the receiver, there being 65 also a wall surrounding the portion of said inner wall within the receiver and serving as a jacket thereabout, said latter jacket communicating with the first-mentioned one through the opening in the receiver wall 70 which supports the first-mentioned jacket.

7. The combination of a receiver having openings in its opposite walls, a jacket mounted on one of said walls, and a cylinder mounted in said jacket and in said openings, 75 said cylinder being secured to said jacket at the end thereof remote from the receiver and entirely outside the zone of combustion and being restrained from movement in its longitudinal direction with reference to said 80 jacket and said receiver only where so secured.

In witness whereof, I have hereunto set my hand this eighteenth day of July, 1912.

KARL STEINBECKER.
